(57) CLAIM

The ornamental design for a combined sports towel and vehicle car seat cover, as shown and described.

DESCRIPTION

FIG. 1 is a front elevational view of a combined sports towel and vehicle car seat cover showing my new design;
FIG. 2 is a rear elevational view thereof;
FIG. 3 is a left side elevational view thereof;
FIG. 4 is a top plan view thereof; and,
FIG. 5 is a bottom plan view thereof.
The broken lines in the drawings represent stitching.
